UNITED STATES PATENT OFFICE.

ARTHUR P. RICHARDSON, OF LOS ANGELES, CALIFORNIA.

FLUSH-TANK SIPHON MECHANISM.

1,311,714.

Specification of Letters Patent. Patented July 29, 1919.

Application filed February 24, 1919. Serial No. 278,798.

To all whom it may concern:

Be it known that I, ARTHUR P. RICHARDSON, a citizen of the United States, residing at Los Angeles, in the county of Los Angeles and State of California, have invented new and useful Improvements in Flush-Tank Siphon Mechanisms, of which the following is a specification:

My object is to make a flush tank siphon mechanism and my invention consists of the novel features herein shown, described and claimed.

Figure 1 is a view showing a flush tank in sectional elevation and constructed in accordance with the principles of my invention. Fig. 2 is an enlarged vertical central section of the siphon mechanism upon the same plane as Fig. 1.

A flush tank box 1 may be any of the usual constructions and has a float operated inlet mechanism 2 and a siphon mechanism 3. The details of the siphon mechanism are as follows:

A large opening 4 is formed through a bottom 5 of the box 1. A flange 6 fits upwardly against the lower face of the bottom 5 to considerably more than cover the opening 4. A neck 7 extends downwardly from the flange 6. An internally screw threaded boss 8 extends laterally from the lower end of the neck 7. A flange 9 extends outwardly from the lower end of the neck 7 below the boss 8, the lower face of the flange being finished. An externally screw threaded nipple 10 extends downwardly from the flange 9. A gasket 11 fits upwardly against the flange 9 around the nipple 10. A cap 12 has a large chamber 13 and a reducing flange 14 at the upper end of the chamber, the reducing flange 14 being internally screw threaded and screwed upon the nipple 10. A boss 15 extends downwardly from the center of the cap 12 and has a kerf 16 for the reception of a tool for screwing on and unscrewing the cap. A neck 17 extends upwardly from the flange 5 loosely through the opening 4. An externally screw threaded enlargement 18 extends upwardly from the neck 17. An extension 19 extends upwardly from the enlargement 18. A web 20 extends part way across the upper end of the extension 19. An externally screw threaded nipple 21 extends upwardly from the web 20 and an externally screw threaded union member 22 extends laterally from the upper

end of the extension 19 below the web 20. A passage 23 extends through the union member 22 and downwardly from the web 20 to the chamber 13. A pipe 24 extends from the web 20 and from the nipple 21 downwardly to the chamber 13. Hollow braces 25 and 26 connect the pipe 24 to the wall of the extension 19, there being passages 27 and 28 through the braces to a passage 29 through the pipe 24. Solid braces 30 and 31 connect the lower portion of the pipe 24 to the wall of the neck 7 so as to hold the pipe 24 centrally in the chamber 23.

An outlet pipe 32 is connected to the boss 8 and leads downwardly. An intake pipe 33 is connected to the union member 22 and extends downwardly to a point just above the bottom 5. A passage 34 leading upwardly through the intake pipe 33 and through the union member 22 downwardly through the chamber 23 and downwardly through the pipe 32 constitutes the siphon proper. A cap 35 is screw seated upon the nipple 21 and has a central opening 36 to form a bearing for a valve stem 37. The valve stem 37 is inserted downwardly through the opening 36 and downwardly through a passage 38 in the pipe 24 to the chamber 13. A valve seat 39 is formed upon the lower end of the pipe 24 and a valve 40 is fixed upon the lower end of the valve stem 37 to fit the valve seat 39. A bracket 41 is clamped to the intake pipe 33 and extends upwardly. A lever 42 is mounted in the upper end of the bracket 41 upon a pivot 43 and is connected to the upper end of the stem 37 by a pin 44. A guide arm 45 extends from the bracket 41 and the long end of the lever 42 extends through the guide arm 45 and a weight 46 is connected to the long end of the lever, the force of the weight being exerted to pull the stem 37 upwardly to bring the valve 40 against the seat 39.

A bearing 47 is mounted on top of the box 1. A lever 48 is pivotally mounted in the bearing 47, a link 49 connects one end of the lever 48 to the lever 42 and the other end of the lever extends over the edge of the box 1. A chain 50 is connected to the outer end of the lever 48 and a handle 51 is connected to the lower end of the chain.

When the inlet mechanism 2 operates, the tank or box 1 is filled to the desired extent, ready for the flushing operation. When it

is desired to flush the bowl 52 or the like, the handle 51 is operated to pull downwardly upon the chain 50, thereby raising the weight 46 and lowering the valve 40 away 5 from the seat 39, then water will pass through the openings 27 and 28 from the chamber 53 and downwardly through the passage 38 to the chamber 13, then upwardly through the lower end of the chamber 23 10 and outwardly and downwardly through the pipe 32. This rush of water will set up the siphonic action, the handle 51 is released, the weight 46 will turn the lever 42 to its normal position and bring the valve 40 15 against the seat 39, and the siphonic action will cause the water in the chamber 53 to pass upwardly through the inlet pipe 33, downwardly through the chamber 23, and outwardly and downwardly through the 20 pipe 32 until the supply of water in the tank is exhausted.

The main casting is inserted upwardly, the union member 22 passing through the opening 4 in the bottom 5, and the flange 6 fitting against the lower face of the bottom. 25 A gasket 5 is placed around the casting against the upper face of the bottom 5, and a flange 18' is screwed down upon the threads 18 against the gasket 17' to hold the 30 parts firmly in place. The cap 12 is below the bottom 5 and in the open air so that when desired the cap may be removed to fix the valve 40.

Of course the upper part of the siphon 35 mechanism is in the box 1 and normally flooded with water. There is a great advantage in connecting the drain pipe 32 to the siphon mechanism outside of the box and in having the cap 12 outside of the box.

40 Various changes may be made without departing from the spirit of my invention as claimed.

I claim:

1. A flush tank siphon mechanism comprising the combination with a flush tank box having a large opening formed through its bottom, of a casting having a flange fitting upwardly against the lower face of the bottom, a neck extending downwardly from the flange, an internally screw threaded boss extending laterally from the lower end of the neck, a second flange extending outwardly from the lower end of the neck be-

low the boss, an externally screw threaded 55 nipple extending downwardly from the second flange, a neck extending upwardly from the first flange loosely through the opening in the bottom of the box, an externally screw threaded enlargement extending upwardly from the neck, an extension extending upwardly from the enlargement, a web 60 extending part way across the upper end of the extension, an externally screw threaded nipple extending upwardly from the web, an externally screw threaded union member extending laterally from the upper end of the extension below the web, there being a passage 65 through the union member and downwardly from the web to the lower end of the first nipple, a pipe extending from the web 70 and from the nipple downwardly to the lower end of the first externally screw threaded nipple, and hollow braces connecting the pipe to the wall of the extension; a 75 cap having a large chamber and a reducing flange at the upper end of the chamber, the reducing flange being screwed upon the first externally screw threaded nipple against the second flange; an outlet pipe connected to the boss and leading downwardly; an intake 80 pipe connected to the union member and extending downwardly to a point just above the bottom; a cap screw seated upon the nipple above the web and having a central 85 opening; a valve stem mounted through the cap and extending through the pipe to the cap chamber; a valve seat at the lower end of the pipe; and a valve upon the valve stem in the cap chamber to fit the valve seat.

2. In a flush tank siphon mechanism, a 90 fitting forming an outer passage and an inner passage, there being a lateral opening to the central part of the inner passage and an opening to the top of the outer passage and both passages being open at the bottom, 95 a chambered cap covering the lower ends of the passages and connecting the lower ends together, a downwardly extending intake pipe connected to the opening at the upper end of the outer passage, and a drain 100 pipe connected to the lower end of the outer passage, there being a valve for controlling the lower end of the inner passage.

In testimony whereof I have signed my name to this specification.

ARTHUR P. RICHARDSON.
